UNITED STATES PATENT OFFICE.

CHARLES W. COFFIN, OF PORTLAND, MAINE, ASSIGNOR TO THE E. T. BURROWES COMPANY, OF PORTLAND, MAINE, A CORPORATION OF MAINE.

CARD-TABLE.

1,247,644.

Specification of Letters Patent. Patented Nov. 27, 1917.

Application filed May 8, 1914. Serial No. 837,159.

To all whom it may concern:

Be it known that I, CHARLES W. COFFIN, a citizen of the United States, residing at Portland, in the county of Cumberland and 5 State of Maine, have invented certain new and useful Improvements in Card-Tables, of which the following is a specification, reference being had therein to the accompanying drawing.

10 The present invention relates to improvements in card tables and the object of the invention is to provide an improved portable, light, folding table of this character, the special light, compact, portable nature 15 of the construction making it particularly fitted for club and domestic purposes.

The invention contemplates a construction including a frame, a relatively light thin top secured to the frame, a covering extending over the top and secured to the frame, and folding supporting legs adapted to be closed into the space within the frame.

An important characteristic of the invention lies in the particular frame construction with the legs pivotally set in or directly interposed and secured at points in the frame structure, the legs with their pivots forming a continuation of and part of the frame. This arrangement makes it 25 possible to employ a relatively small frame while still permitting of the folding of the legs into the space within the frame. Metal brackets and the like usually employed to attach the legs to the frame are dispensed with, the structure produced being very simple and compact.

Another important characteristic of the invention resides in the provision of a relatively light, thin, broad border projecting 40 beyond the frame and forming a substantial continuation of the light thin top, the playing surface of the table being thus increased and the legs given a position somewhat removed out of the way from the outer edge 45 of the table.

Important novel features of the invention also reside in the particular construction of the frame to receive the border and top, and the relative arrangement and connection of 50 these parts, the border serving as means for fastening the cover at the edges to the frame, furnishing an ornamental finish, and bridging the frame at point of insertion of the legs reinforces the same at these places.

55 The invention will be clearly understood

from the following detailed description, when considered in connection with the accompanying drawings forming a part hereof and illustrating one embodiment of the invention.

60

In the drawings:

Figure 1 is a perspective view of the table constructed in accordance with the present invention.

Fig. 2 is a plan of one corner portion of 65 the table with the parts shown in section.

Fig. 3 is a vertical section on the line 3—3 of Fig. 2.

Fig. 4 is a detailed view of an end portion 70 of one of the bars of the frame.

Fig. 5 is a bottom plan view, with parts broken away showing in the lower portion of the figure the construction of the frame without the top and border.

Fig. 6 is a vertical section on the line 5—5 75 of Fig. 5 looking in the direction of the arrow.

The drawings illustrate a preferred embodiment of the invention and in this particular instance the frame is shown as of rectangular shape including in its construction bars 1 arranged with their adjacent end portions overlapping and separated from each other, and in the spaces between the ends of the bars are pivotally secured supporting 80 legs 2, which are adapted to fold into the space within the frame. Metal washers 3 and spacing blocks 4 are also interposed in the structure at the sides of the legs and the parts are connected to complete the frame 85 by fastening members 5 passing transversely through the end portion of one bar through the washers, spacing blocks and legs, and extending into the adjacent end portion of the other bar. The fastening members conveniently take the form of stout screws with 90 relatively long shanks to extend well into the end portions of the bars and afford a firm connection between the bars, the screws having unthreaded smooth inner portions 95 100 constituting pivots for the legs.

By constructing the frame with the legs interposed and pivotally secured at points in the frame structure in the manner set forth, a very simple, cheap and compact construction is produced. This construction enables the use of a relatively small frame and top while at the same time permitting of the folding of the legs into the space within 105 the frame. Separate metal brackets and the 110

like usually employed to attach the legs to the frame are dispensed with, the means for connecting the ends of the bars also serving as pivots for the legs, the construction being 5 of a character which facilitates the quick assembling and connection of the parts.

The frame has a top supporting surface 7 and an outer seat or rabbeted portion 8 having its bottom 9 below the plane of the 10 top supporting surface 7, the bars 1 being gained out or rabbeted at the sides and ends for this purpose. 10 designates a relatively light thin top, preferably of paper although any other suitable material may be employed. The top is substantially coextensive 15 with the top supporting surface 7 of the frame and is secured to the upper face of the frame in any suitable manner, for instance, as shown in the drawing by small tacks. A cover 11 of felt or other suitable material is stretched over the top, marginal portions of the cover being brought down into the rabbeted portion and suitably secured at the bottom thereof. In the drawing, 20 the bottom wall of the rabbeted portion is shown as provided with a groove 12 and the marginal edge portions of the cover located in the groove and secured by small tacks.

30 A relatively light thin broad border is provided and secured to the frame with its inner portion resting in the rabbeted portion 8, the border projecting beyond the frame and constituting a substantial continuation of the top 10. The border 13 is secured to the frame by screws 14 or other suitable fastening means, the border being placed in position after the cover has been applied, marginal portions of the cover depending between the inner edge of the border and frame and extending to the under side of the border, the border serving to hold the marginal edges of the cover in place and to conceal the same from view.

45 As illustrated in the drawing the upper face of the cover preferably occupies a position slightly raised with reference to the inner edge of the border so that the inner edge of the border will not offer any obstruction in 50 withdrawing cards from the table over said edge. The border is shown as of rectangular shape and composed of relatively thin, broad, light strips of polished wood rigidly connected at their ends by miter joints, as 55 shown, connecting plates or flat dowels 15 uniting the ends of the strips and reinforcing the border at the corners thereof. It will be noted that the border, which is firmly connected to the bars of the frame extends 60 over and bridges the frame at the places in the frame where the legs are inserted reinforcing the frame at these points. The broad smooth polished border rail increases 65 the playing surface and provides a highly ornamental finish, serving to conceal the

connection of the marginal edges of the cover with the frame and also as additional fastening means to hold the cover in place on the frame.

Any suitable construction of braces 16 70 for the legs may be employed and the top 10 may be reinforced, as desired, strips 17 being shown secured to the under side of the top for this purpose.

It will be understood that the specific 75 embodiment of the invention illustrated in the drawings may be changed or modified, within the scope of the appended claims without departing from the nature or principle of the invention.

What I claim is:

1. In a card table, the combination of a top, a frame for supporting the top, said frame structure having openings therein at intervals and supporting legs foldably secured to the frame in the said openings in the frame structure, the legs being adapted 85 to fold into the space within the frame.

2. A card table comprising a rectangular shaped frame, including side and end bars, 90 the adjacent ends of the bars at the corners being separated, supporting legs interposed in the spaces between adjacent ends of the bars, and fastening members connecting the bars and pivotally connecting the legs in the 95 frame, and said legs being adapted to fold into the space within the frame.

3. A card table comprising a rectangular shaped frame including side and end bars, the adjacent ends of the bars at the corners 100 being separated and extending in overlapped relation, supporting legs in the spaces in the ends of the bars, and fastening devices connecting adjacent ends of the bars and pivotally connecting the legs in the frame, 105 said fastening devices passing transversely through the end portion of one bar and extending longitudinally of and into the adjacent end portion of the other bar, said legs being adapted to fold into the space 110 within the frame.

4. A card table comprising a frame having a top supporting surface, and an outer seat below the plane of the top supporting surface, a relatively thin light top secured 115 to the upper face of the frame, a border constituting an extension of the top and projecting beyond the frame, the inner portion of the border resting in the said seat, means for securing the border to the frame, 120 and a cover stretched over the top and having marginal portions extending between the border and the frame, the border serving to secure the cover at the edges to the frame.

5. A card table comprising a frame having a top supporting surface and an outer rabbeted portion with its bottom below the plane of the top supporting surface, a relatively thin light top secured to the upper face of the frame, a cover stretched over the 130

top and having marginal portions extending into the said rabbeted portion and a relatively thin broad border having its inner edge resting in the rabbeted portion of the frame over the marginal portions of the cover, said border projecting a substantial distance beyond the frame and constituting an extension of the top.

5 6. A card table comprising a frame, portions of the frame being separated to provide spaces in the frame structure, a top secured to the frame, supporting legs pivotally secured in the spaces in the frame, and a border secured to the frame bridging and 10 reinforcing the frame at the points of insertion of the legs.

15 7. A card table comprising a frame, portions of the frame being separated to provide spaces in the frame structure, supporting legs pivotally secured in the spaces in the frame, said frame having a top supporting surface and an outer seat below the plane of said supporting surface, a relatively thin light top secured to the upper 20 face of the frame, a border constituting an extension of the top and projecting beyond the frame, the border being secured to the frame with its inner portion resting upon the said seat and overlying and bridging the 25 frame at the points of insertion of the legs.

30 8. A card table comprising a frame, a top supporting surface and an outer rabbeted portion with its bottom below the plane of said supporting surface, a relatively thin light top secured to the upper face of the frame, a border constituting an extension of the top and projecting beyond the frame, the inner portion of the border resting in the rabbeted portion, means for securing the 35 border to the frame, a cover stretched over the top and provided with marginal portions extending between the border and the bottom of the rabbeted portion, said rabbeted portion being provided with a groove in its 40 bottom to receive the marginal edge portions of the said cover.

45 9. A card table comprising a frame, portions of the frame being separated to provide spaces in the frame structure, supporting legs pivotally secured in the spaces in the frame, said frame having a top support-

55 ing surface and an outer seat below the plane of said top supporting surface, a relatively thin light top secured to the upper face of the frame, a border constituting an extension of the top and projecting beyond the frame, the border being secured to the frame with its inner portion resting in the said seat and bridging the frame at the points of insertion of the legs, said border 60 being recessed at its under side to accommodate the legs, said legs being adapted to fold into the space within the frame.

65 10. A card table comprising a frame, portions of the frame being separated to provide spaces in the frame structure, supporting legs pivotally secured in the spaces in the frame, said frame having a top supporting surface and an outer seat below the plane of said top supporting surface, a relatively thin light top secured to the upper 70 face of the frame, a border constituting an extension of the top and projecting beyond the frame, the border being secured to the frame with its inner portion resting in the 75 said seat and bridging the frame at the points of insertion of the legs.

80 11. A card table including a frame comprising a plurality of sections, the adjacent ends of the sections being separated, supporting legs interposed in the spaces between adjacent sections and fastening means connecting the sections together and pivotally connecting the legs in the frame, said legs being adapted to fold into the space 85 within the frame.

90 12. In a card table, the combination of a top, a frame for supporting the top comprising a plurality of sections, the adjacent ends of the sections being separated, and supporting legs foldably secured to the frame in the spaces between the ends of adjacent sections of the frame, said legs being adapted to fold into the space within the 95 frame.

In testimony whereof I hereunto affix my signature in the presence of two witnesses.

CHARLES W. COFFIN.
